UNITED STATES PATENT OFFICE.

WILLIAM H. ROHR, OF PORTLAND, MAINE.

CARBURETER.

1,232,847.

Specification of Letters Patent. Patented July 10, 1917.

Application filed April 23, 1915. Serial No. 23,480.

To all whom it may concern:

Be it known that I, WILLIAM H. ROHR, a citizen of the United States, residing at Portland, in the county of Cumberland, State of Maine, have invented certain new and useful Improvements in Carbureters for Explosive-Engines; and I do hereby declare the following to be a full, clear, and exact description of the invention, such as will enable others skilled in the art to which it appertains to make and use the same.

This invention relates to carbureters for explosive engines.

The object of the invention resides in the provision of a carbureter which will be exceedingly simple in construction, economical with respect to the consumption of gasolene, and extremely flexible.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a view in elevation of a carbureter constructed in accordance with the invention;

Fig. 2, a vertical section of same; and

Fig. 3, a section on the line 3—3 of Fig. 1.

Referring to the drawings the carbureter is shown as comprising a casing A which includes a gasolene reservoir 10 provided with a gasolene intake opening 11 adapted to be closed by a valve 12, said valve being controlled by a float 13 to maintain the gasolene in the reservoir 10 at a predetermined level all in the usual and well known manner. Disposed within the reservoir 10 is a cylindrical partition 14 which is extended beyond both the top and bottom of the reservoir and terminates at its upper end in a securing flange 15 whereby the carbureter may be attached to the manifold of an explosive engine. The space within the cylindrical partition 14 is divided by a longitudinal partition 15 into air passages 16 and 17, the former having considerably less cross sec-

tional area than the latter. The upper end of the passage 17 is closed as at 18, while the partition 15 is provided with an opening 19 controlled by a spring valve 20. Mounted in the extension of the partition 14 above the upper end of the passage 17 is a throttle valve 21. The flow of gasolene from the reservoir 10 to the passage 16 is controlled by a needle valve 22, while the flow of gasolene from the reservoir 10 to the passage 17 is controlled by a needle valve 23.

In the use of a carbureter constructed as described it will be apparent that when the engine is throttled down or running on low speed the necessary quantity of air can be drawn through the passage 16 and under such conditions the valve 20 will remain closed so that no air will travel through the passage 17. When the throttle valve 21 is opened the required quantity of air cannot get through the passage 16 and as a result the suction of the engine will open the valve 20 and permit the requisite quantity of air in addition to that supplied through the passage 16 to pass through the passage 17 and through the opening 19 thus maintaining the proper mixture irrespective of the speed of the engine with which the carbureter is associated.

What is claimed is:

A carbureter comprising a casing having a liquid fuel chamber and a pair of parallel air passages extending axially through the fuel chamber and having different cross sectional areas, and further having a common wall provided with an opening affording communication between said passages, the end of the passage having the greater cross sectional area and which is adjacent said opening being closed, a spring valve operatively mounted in the casing for axial movement transversely of the passages and normally closing said opening, and means for supplying liquid fuel from the fuel chamber to each of said air passages.

In testimony whereof, I affix my signature, in the presence of two witnesses.

WILLIAM H. ROHR.
